UNITED STATES PATENT OFFICE

RUDOLF MUHLICHEN, OF HOBOKEN, NEW JERSEY

EXTENSION TABLE

Application filed October 16, 1928. Serial No. 312,914.

This invention relates to extension tables. One object of this invention is to provide an extension table in which the extension sections, either singly or in multitude, may be automatically placed by simply pulling the two table sections apart.

A further object of my invention is to provide in combination with such table, means for automatically elevating one or more extension sections into level position with the table top and to automatically depress such extension sections by closing the table sections.

Another object of my invention is to provide with each extension section, means for supporting it in its elevated position.

A further object of my invention is to provide in connection with such table, guide means strengthening the table while in its extended position.

The foregoing and further objects will be more fully apparent from the following description and the accompanying drawings, forming part of this disclosure, and in which

Figure 1 represents a preferred embodiment of the upper portion of a table in its closed position,

Figure 2 is a side elevation of the upper portion of a table with one side extension,

Figure 3 is a similar elevation of such table portion with both sides extended,

Figure 4 is a bottom view of the table in extended position,

Figure 5 is a cross sectional view, taken on line 5—5 of Figure 4,

Figure 6 is a cross sectional view, taken on line 6—6 of Figure 4,

Figure 7 is a detail cross sectional view showing the disappearing table top extension support,

Figure 8 is a detail view, partially in cross section of a section elevator, and

Figure 9 represents different cross sectional views of modified table tops and table top extensions.

Referring to the figures, numeral 10 denotes the left hand table section and numeral 11 the right hand table section. Each of the table sections consists of table tops 12 and 13 and frame members 14 and 15. The latter

are provided with longitudinal recesses 16 and 17, adapted to accommodate table top extensions 18 and 19 when the table sections are in abutting position.

The underframes 14 and 15 are connected with each other by means of rails 20, provided with longitudinal slots 21, which are engaged by pins 22 equally lodged within the frame members, as clearly seen in Figure 7. The center portions of rails 20 are connected at 23 with substantially I-shaped bridge 24 which is supported at its broadened center by means of a central leg 25.

Associated at the side extensions 26 of the I-shaped bridge 24 are table extension elevating devices 27, shown in detail in Figure 8, and consisting of a cylindrical member 28, in which is mounted a plunger 29 permanently attached to table top extension 19, as indicated at 30. Depending from plunger 29 is a rod 31 at the end of which is provided stop member 32, which limits the upward movement of plunger 29.

Wound about rod 31 and bearing against plunger 29 is an expansion spring 33, adapted to elevate plunger 29 and thereby the extension section 19. These elevating devices 27 are symmetrically arranged relative to the extension sections.

When one half of the table is pulled out, as shown in Figure 2, the right hand extension section 19 is released from recess 17 and is propelled upwards by the spring controlled elevators 27. When both sections are pulled from each other, section 18 and section 19 are elevated into a position level with table tops 12 and 13.

Attached at the bottom face of each extension section are provided supporting means, indicated at 34 and seen in detail in Figure 7. These supports consist of a stationary plate 35, provided with hinge 36 to which is connected a leg 37, normally held in place by a spring 38. When this spring is pushed upwards, as indicated by arrow, member 37 will fall by its own weight into the broken line position, describing an arc, indicated by another arrow.

The broadened face of leg 37 is adapted to rest against connecting rail 20 above which

extends section 18, now supported. The arrangement of these supporting means is essential when it is considered that spring 33 of the elevators are only intended to support the weight of the extension sections. Additional weight would depress these sections, and therefore supports 34 are provided.

Connecting the ends of the underframes are telescoping guide members 39, adapted to reinforce the table when in its extended position.

In Figures 1, 2, 3 and 4, the table tops 12 and 13 and also the extension members 18 and 19, are shown to have straight abutting faces. In Figure 9 there is shown table tops 12' and 13' having beveled edges 12'' and 13''. There is also shown an extension section 19' with a beveled extension edge 19''. This construction is particularly adapted to facilitate the closing of the table. When the table sections are pushed towards each other, extension section 19 will be automatically depressed into its downward position and thereby facilitate the closing of the table. It is obvious that the abutting edges of the extensions in such case would be straight while the edges engaging the table tops 12 and 13, can be shaped, as shown in Figure 9.

In Figures 4 and 5, there will be seen at the bottom edge of the table top members 12 and 13, friction reducing elements 40, adapted to reduce contact between the bottom face of the table top members and the upper face of the table top extensions. If these friction reducing members would not be provided, the friction between the two faces would be excessive, and furthermore, top face of the extension sections might be unnecessarily damaged.

In Figures 4, 5 and 6, it will be seen that the legs of the tables, except center leg 25, are supported by specially constructed bridges 41, so arranged as to accommodate telescoping guide members 39.

While I have shown and described specific forms of my device, be it understood that I shall not be limited to the actual showing. Thus, more than two top extensions may be provided. They also may be set one on top of each other and consequently slots 16 and 17 would have to be made wider to accommodate the additional leaves. Similarly, I shall not be limited to the stationary construction of bridge 24. It is obvious that in the case of employment of more than two leaves, an appropriate arrangement of the elevators would have to be provided.

I therefore reserve for myself the right to make such changes and improvements within the scope of my invention, for which I claim:—

1. The combination with an extension table including a pair of table sections consisting of table tops and underframes, the latter provided with recesses for accommo-

dating top extension sections when the latter are not in use, of cross members or bridges located near the ends of and associated with said table sections and adapted to serve for support of the table legs, telescoping guide members associated with the ends of the underframes of said table sections and extending from one end to the other and operatively mounted within the spaces formed by said bridges, a pair of symmetrically slotted side rails or skirts slidably associated with the sides of the underframes, a central bridge associated with said side rails and having a plurality of means for supporting the top extension sections when the table is extended. 70

2. The combination with an extension table, including a pair of table sections composed of table tops and underframes, the latter having end and side members, said side members provided with recesses for extension top sections lodged in said recesses when not in use; of cross members or bridges located near the end members of the underframe and serving for supports for table legs, a plurality of telescoping guide means associated with the end members of the underframe and extending below the top from one end to the other end of the table sections and passing through the space provided in said bridges, a pair of symmetrically slotted side rails or skirts slidably associated with the side members of said underframe, a central bridge centrally attached to said skirts and provided with a plurality of spring controlled elevators for supporting table top extension sections when the latter are used, table top extension sections normally lodged in the recesses provided in the side members of the underframe and adapted to be propelled upwards when put to use by said elevators and collapsible supporting means provided with said extension sections for supporting them upon said side rails or skirts when in use. 85

In testimony whereof I affix my signature.

RUDOLF MUHLICHEN.
